UNITED STATES PATENT OFFICE.

THEODORE E. STRAUS, OF BALTIMORE, MARYLAND, ASSIGNOR TO WORTHINGTON
COTTON HARVESTER COMPANY, OF BALTIMORE, MARYLAND, A CORPORATION
OF DELAWARE.

COTTON-PICKER.

1,110,158.

Specification of Letters Patent. Patented Sept. 8, 1914.

Application filed October 2, 1912. Serial No. 723,519.

To all whom it may concern:

Be it known that I, THEODORE E. STRAUS, a citizen of the United States, residing at 10 South street, Baltimore, State of Maryland, have invented certain new and useful Improvements in Cotton-Pickers, of which the following is a description, reference being had to the accompanying drawing and to the figures of reference marked thereon.

10 The invention relates to new and useful improvements in cotton pickers and more particularly to the construction of the picking nozzle which removes the cotton fiber from the cotton boll and directs the same to a suction controlled intake passage.

An object of the invention is to provide a picking nozzle in which the parts shall be of simple construction and readily accessible for the changing of the picker teeth, if the 20 same become bent or broken.

A further object of the invention is to provide a picking device wherein the parts which support the picking fingers are housed within the casing forming the nozzle, whereby said operated parts may be kept free from the cotton fiber.

A further object of the invention is to provide an improved form of picking tooth and supporting means therefor, whereby a 30 single tooth may be removed and replaced without requiring the disassembling of the parts of the picking device.

These and other objects will in part be obvious, and will in part be hereinafter 35 more fully disclosed.

In the drawings, which show by way of illustration, one embodiment of the invention, Figure 1 is a longitudinal sectional view through a picking nozzle, having my 40 improvements applied thereto, said section being centrally of the intake passage and also centrally of one of the supporting drums or carriers for the picking teeth. Fig. 2 is a partial bottom plan view, and 45 partial sectional view through the clutch mechanism, the stripping devices and one of the side plates being removed, while the other is in section. Fig. 3 is an end view of the picker nozzle with the front plate re- 50 moved. Fig. 4 is a perspective view of the carrier or drum for supporting the picking fingers, showing the supporting rods with the picking fingers removed therefrom. Fig. 5 is a longitudinal sectional view through 55 the carrier or drum for the picker fingers,

showing the picker fingers in section, and also the collars for spacing the same in section. Fig. 6 is an end view of the drum or carrier with the front cap and the supporting rods for the picker fingers 60 removed. Fig. 7 is a similar view showing the supporting rods for the picker fingers in place and in section. Fig. 8 is an end view of the drum or carrier for the picker fingers showing one set of picker fingers 65 and the rods for supporting the same in section. Fig. 9 is a front view of the retaining cap for the drum or carrier.

My improved picking device consists of a casing 1, having an intake passage 2, and 70 an intake picking mouth 3, which extends transversely of the casing. Said casing at its inner end is in the form of a sleeve adapted to be attached to a flexible conveying pipe, which, in turn, is connected to a suitable source of suction. Said casing is extended laterally and downwardly so as to 75 form the picking head which is provided with the picking mouth above referred to. The intake passage 2 of the casing extends 80 through to the picking mouth. The casing is formed with a side wall 4, which extends transversely of the nozzle, and a front wall 5, which is substantially parallel with the wall 4. The walls 4 and 5 are joined by end 85 walls 6 and 7. These end walls 6 and 7 are preferably curved, as shown in Fig. 3, so as to provide a suitable housing for the picking devices 8 and 9, which are disposed at each side of the intake passage. The lower 90 part of the casing is cut away at each side of the intake passage so as to provide inclined faces 10 and 11, which faces are inclined outwardly from the extreme side edges of the nozzle toward the center plane 95 of the nozzle. The front wall 5 of the nozzle is cut away from a point substantially at the outside of one picking device to a point substantially at the outside of the other picking device, and also to a point substantially 100 in line with the center of the main intake passage 2. The edges of the side wall 5 are formed with a groove 12, and a closing plate 13 is adapted to slide in the groove and close the casing where the same is cut away. A pin 14 is secured to the casing 1, and said plate 13 is formed with an opening adapted 105 to spring over the pin, and which acts to hold the plate in position.

The casing 1 is formed with a second wall 110

15, which is substantially parallel with the wall 4, and spaced therefrom, but joined thereto at its outer ends so as to provide a chamber 16. The wall 4 is formed with projecting bearings 17, which extend into the chamber 16, and form a support for the picker drums or carriers 18 for the picker fingers. These picking devices 8 and 9 are similar in construction, and, therefore, the 10 description of one will answer for the other. The inwardly projecting bearing 17 is bored to receive a hardened sleeve 19, in which the drum or carrier 18 rotates. This drum is formed with a central opening through 15 which extends a shaft 20, which shaft projects beyond the drum and extends through a suitable opening in the wall 15. The shaft is held rigid in said opening by a set screw 21^a. Said shaft is shouldered, as 20 shown in the drawings, so as to rest against the inner face of the casing. This shaft carries at its inner end a cam 21, which operates to hold the picker fingers rigid at certain times during their rotation. The picker 25 fingers 22 are mounted upon supporting rods 23. These supporting rods extend the length of the drum and project beyond the inner end thereof. The drum is formed with spaced recesses for said rods. Each 30 rod is formed with a projecting lug 24, which is so disposed in the drum as to cooperate with the cam 21. The drum is cut away, as at 25, so as to allow the projecting lug 24 to turn so that said lug may pass the cam 21. When this cam 21 is positioned so 35 as to cover the cut away part 25, the lug 24 will be fixedly held in said recess, which will prevent the rod 23 from rotating, and this will hold the picker fingers carried by the 40 rod rigid. As soon, however, as the cut away part is uncovered, then the lug can swing toward the center of the fixed shaft 20, and the picker fingers will be released, so that they may oscillate, to a limited extent, about the axis of the supporting rods 45 therefor. The supporting rods for the picker fingers are held in the drum by a face plate or cap 26, which is secured to the drum by suitable screws. This face plate is formed 50 with openings 27, through which the rods project.

The rods supporting the picker teeth extend from the drum through the openings 27 in the face plate, and the face plate practically closes the interior of the drum, so 55 that the parts may be properly lubricated.

The face plate engages the adjacent face of the lug 24 which holds the rods in the drum, and permits a free movement thereof, 60 when said lug is out of engagement with the fixed cam. The fixed cam also serves to hold the drum from endwise movement on the fixed shaft, as said fixed cam will engage the drum at one face, while at its other face said 65 cam engages the face plate or cap.

The supporting rod for the picker fingers is flattened on one face as at 28. The picker teeth are preferably stamped from sheet metal, and are formed with an opening which has a flat face, so that the opening in 70 the picking tooth corresponds in shape to the cross sectional shape of the supporting rod. This construction allows the picker tooth to be readily slipped endwise on the supporting rod, and when placed on the rod, 75 said flat face will prevent the tooth from turning relative to the rod. A collar 29 is first placed on the rod, which rests against the face plate of the drum. A picker tooth is next slid on the rod, after which a spacing 80 collar 30 is slid on the rod, then a second picker tooth is placed on the rod, and then another spacing collar, and finally the third picker tooth. A nut 31 is then threaded on to the end of the supporting rod 23, which holds the picker teeth from endwise movement on the rod. A set nut 32 may also be threaded on to the end of the supporting rod 23. The collars 30 are preferably of slightly 85 less outer diameter than the shank of the 90 picker finger.

From the above it will be apparent that I have provided a construction of picker, wherein a picker drum or carrier is entirely housed within the casing, and at a point one 95 side the picking mouth and intake passage, so that the cotton fiber cannot work into the operating parts and clog the same. Furthermore, by the above construction, the picking fingers may be readily removed and replaced 100 without disassembling the parts of the drum, and the actuating mechanism for the picker fingers. Also, I have provided a construction whereby the supporting device for the 105 picker fingers may be readily removed and replaced.

The picker fingers, as above noted, are stamped from sheet metal, and are formed so that the active picking face 33 is preferably on a line which is substantially radial 110 to the axis of the supporting rod for the finger. The outer face 34 of the picking tooth is substantially tangential to the shank of the tooth. The tooth is also made relatively wide to a point 34, which is adjacent the extreme point of the picking finger, from 115 which point the tooth is curved to the picking face thereof. By this shape of tooth, I have provided a picking finger or tooth which is extremely strong at its outer active end, and the picking face of the tooth is always at right angles to a plane tangential to the path of movement of any point in the active face of the picker finger, and thereby, 120 the cotton fiber which is engaged by the tooth will be carried along with the tooth until it reaches a point where the tooth is released and is free to turn backward to allow the cotton to be stripped therefrom.

In order to strip the cotton fiber from the 125 130

picking fingers, I have provided stripping plates 36 and 37. These plates are similar in construction, but oppositely disposed in the nozzle. The plate 36 is secured to the extreme outer end wall 6, and projects inwardly where it is curved to conform substantially to the curvature of the drum to a point 38, and from this point said stripping plate 36 is substantially straight and parallel with a plane passing centrally through the nozzle and intake passage. The plate 37 is similarly shaped and is attached to the extreme outer wall 7. These plates 36 and 37 at their outer ends are substantially parallel and are free, said plates being supported solely by the end walls 6 and 7. Each plate 36 and 37 is slotted so as to provide a space for the passage of the picking fingers. The cotton fiber which is carried by the picking fingers will be drawn against the stripping devices, and the fingers, being released so that they may turn, will be carried backward and gradually withdrawn from the fiber, which will lodge against these stripping devices and be drawn by suction between the same into the intake passage 2.

As a means for stripping or removing the burs and twigs from the picking fingers, and for holding back the parts of the burs while the cotton fiber is being stripped from the boll, I have provided stripping fingers 39 and 40. These stripping fingers are attached to the end walls 6 and 7 respectively, and are substantially straight, but arranged so as to incline outwardly toward the center plane of the nozzle, and lie substantially in the plane of each inclined picking face of the nozzle. Said fingers terminate practically at the point where the extreme point of the picker finger crosses the plane of the picking face, so that any bur or twig caught by the picking finger will be gradually moved along the active face thereof, and released from the picking point before the picking finger passes into the picking mouth, and reaches the range of suction through the intake passage. The end wall 13 also extends outwardly in a direction longitudinal of the intake passage, as at 41, and said plate is bent inwardly over the picking mouth, and is formed with an outwardly turned lip 42.

The chamber 16 is closed by a cover plate 43, which, at a point adjacent the wall 4, is bent outwardly at 44, and is formed with a lip 45, which outwardly bent portion and lip are substantially spaced the same as the lower edge 41 and lip 42 of the plate 13. The inclined faces 46 and 47 of the plate 13 and the cover plate 43 serve as stripping faces in the same manner as the stripping fingers 39 and 40. These inclined stripping faces on the side plates and the general arrangement of the picking devices relative to

the intake passage form no part of the present invention, but are shown, described and claimed in my co-pending application, Serial No. 663,747, filed December 4, 1911, patented July 15th, 1913, No. 1,067,282. 70 The stripping fingers extending between the picking devices, together with the other elements coöperating therewith also form no part of the present invention, but are shown, described and claimed in my co-pending application, Serial No. 670,248, filed January 9, 1912. 75

As a means for operating the rotating carriers and drums, which support the picker fingers, I have provided the picking device 8 with a gear 48, which is attached in any suitable way to the rotating drum 18, and the picking device 9 with a gear 49, similarly attached to the drum of said picking device. A driving gear 50 meshes directly with the gear 49, and transmits motion to the gear 48 through an intermediate idler 51. Through this gear connection both of the drums will be rotated, but in opposite directions. The main gear 50 is carried by 80 a short shaft, which is mounted in a suitable bearing 52. This shaft is in the form of a sleeve, through which passes the main driving shaft 53. A cone 54 is rigidly secured to the driving shaft 53 and is adapted to 85 coöperate with a cone-shaped recess 55 in the inner end of the shaft or sleeve carrying the gear 50. The shaft 53 at its outer end is suitably connected to the flexible driving shaft 56 so that the shaft 53 may slide longitudinally relative thereto. A spring 57 bearing against a collar 58 on the shaft 53 normally moves said shaft so that the friction cone 54 is held in driving engagement with the wall of the recess in the end of the 90 shaft carrying the gear 50. By this frictional driving, it will be readily seen that if a picker finger strikes a hard substance in such a manner as would break the parts, the sections of the friction clutch will slide one 95 upon the other, allowing the picker fingers to stop while the movement of the shaft continues. The parts of the clutch are separated by a turn button 58, the shank 59 of which extends through the wall of the projecting casing housing the parts of the clutch, and is bent laterally at 60. When the laterally bent part 60 is moved into engagement with the collar 58, said collar will be moved in a direction to compress the spring 100 57 and separate the parts of the friction clutch. The casing for the flexible shaft 56 telescopes within the projecting part of the casing 1, and is held therein by a spring latch 61, which is formed with a lug 62, 105 adapted to engage an annular recess in the sleeve on the end of the casing of the flexible shaft.

The operation of my device will be apparent from the above description. The 110

1
picking fingers are so disposed as to move from a point within the mouth of the picking device at each side of the nozzle, to a point beyond the picking mouth and into the intake passage. The nozzle is presented to the cotton boll so that the picking fingers will engage the cotton fiber. The stripping devices will hold back the burs and twigs, while the cotton is stripped therefrom, and 5 said stripping devices will remove the burs and twigs from said fingers at points outside of the range of suction, so that substantially only clean cotton fiber is carried by the picking fingers to the intake passage. 10 The inwardly bent parts of the plates at each side of the nozzle project beyond the path of travel of the picking fingers and separate the nozzle into two picking regions, one at each side of said intake passage. One face of the picking nozzle may, therefore, be presented to the cotton boll, and by turning the nozzle axially, the other face brought into active picking relation thereto, while the stripping plates protect 15 the picking mouth in a plane centrally thereof, so that the burs and twigs will not be drawn in by suction to the intake passage, as the nozzle mouth is passed by the same.

It is obvious that minor changes in the 20 details of construction and the arrangement of parts may be made without departing from the spirit of the invention, as set forth in the appended claims.

Having thus described my invention, what 25 I claim is:—

1. A picking device comprising a casing having a picking mouth and intake passage, a rotating carrier mounted in said casing at one side of said picking mouth, a plurality 30 of supports mounted in and supported by said carrier and projecting longitudinally therefrom into said picking mouth, and picker teeth mounted on said supports.

2. A picking device comprising a casing 45 having a picking mouth and an intake passage, a rotating carrier mounted in said casing at one side of said picking mouth, picker supports mounted in and supported by said carrier and projecting longitudinally there- 50 from and picking fingers carried by said supports, said carrier having means for holding said fingers rigid while the cotton is being removed from the boll, and for releasing said fingers while the cotton is being 55 stripped from said fingers.

3. A picking device comprising a casing having a picking mouth and intake passage, a rotating carrier mounted in said casing at one side of said picking mouth, supports 60 mounted in and supported by said carrier and projecting longitudinally therefrom into said picking mouth, picker teeth mounted on said supports, and stripping devices for stripping the cotton from the fingers in said intake passage.

4. A picking device comprising a casing having a picking mouth and an intake passage, a rotating carrier mounted in said casing at one side of said picking mouth, picker supports mounted in and supported by said carrier and projecting longitudinally therefrom and picking fingers carried by said supports, said carrier having means for holding said fingers rigid while the cotton is being removed from the boll, and for releasing said fingers while the cotton is being stripped from said fingers, and stripping devices for stripping the cotton from said fingers in said intake passage. 70 75

5. A picking device comprising a casing 80 having a picking mouth extending transversely of the casing, and an intake passage connected therewith, a picking device at each side of said intake passage, each picking device including a rotating carrier located at one side of the picking mouth, picker finger supports mounted in each carrier and projecting into the mouth, a plurality of picker fingers mounted on each support, and means for stripping the cotton 85 from the picker fingers in said intake passage. 90

6. A picking device comprising a casing having a picking mouth extending transversely of the casing, and an intake passage 95 connected therewith, a picking device at each side of said intake passage, each picking device including a rotating carrier located at one side of the picking mouth, picker finger supports mounted in each carrier and 100 projecting into the mouth, a plurality of picker fingers mounted on each support, means for stripping the cotton from the picker fingers in said intake passage, and means for removing the burs and twigs from 105 the picker fingers at points outside of said intake passage.

7. A picking device comprising a rotating carrier, a picker finger support mounted in and supported solely by said carrier and projecting longitudinally therefrom, picker fingers removably connected with said support, spacing collars for spacing said fingers, and means for securing the fingers on 110 said supports. 115

8. A picking device comprising a rotating carrier, picker finger supports mounted in and supported solely by said carrier and projecting longitudinally from the end thereof, picker fingers mounted to move 120 freely endwise on said support, spacing collars for spacing said fingers, means for preventing said fingers from turning on said supports, and means for holding the fingers on said supports.

9. A picking device comprising a rotating carrier, picker finger supports mounted in and supported by said carrier, and projecting longitudinally therefrom, each support having a flattened face, picker fingers 130

carried by each support, and having a flat face to engage the flat face on the support, whereby said fingers are held from movement on said support, means for spacing 5 said fingers, and means for holding the fingers on said support.

10. A picking device comprising a casing having parallel transverse inner and outer walls forming a picking mouth, and an intake passage leading from said mouth, a picking device including a rotating carrier mounted in said inner wall, and substantially flush with the face thereof, picker finger supports mounted in said carrier and projecting beyond the inner wall into said picking mouth, picker fingers carried by said supports, and means for stripping the cotton fiber from said picker fingers.

11. A picking device comprising a casing having parallel transverse inner and outer walls forming a picking mouth, and an intake passage leading from said mouth, a picking device including a rotating carrier mounted in said inner wall, and substantially flush with the face thereof, picker finger supports mounted in said carrier and projecting beyond the inner wall into said picking mouth, picker fingers carried by said supports, and means for stripping the cotton fiber from said picker fingers, said outer wall being cut away, and a removable plate for closing said cut away portion of the outer wall, whereby access may be readily had to said picker fingers.

12. A picking device comprising a rotat- 85 ing drum having a recess formed centrally thereof, a stationary shaft supporting said drum, a cam carried by said shaft, a plurality of picker finger supports mounted in said drum, and each having a lug adapted to engage the cam carried by the fixed shaft, said picker finger supports projecting from the end of the drum, a cap secured to the end of the drum for holding said supports in the drum, and picker fingers carried by 45 said supports.

13. A picking device comprising a casing having transverse parallel walls forming a picking mouth, an intake passage leading from said mouth, said casing having a wall 50 parallel with said inner wall and forming a chamber, a picking device including a rotating carrier mounted in said inner wall, a gear for operating said carrier located in said chamber, a driving gear for engaging 55 said gear on the carrier, also located in said chamber, picker finger supports mounted in said carrier and projecting into said picking mouth, picker fingers mounted on said supports, and means for closing said chamber. 60

In testimony whereof, I affix my signature in the presence of two witnesses.

THEODORE E. STRAUS.
